UNITED STATES PATENT OFFICE.

HUBERT C. HART, OF UNIONVILLE, CONNECTICUT.

DESIGN FOR A KNIFE OR FORK HANDLE.

SPECIFICATION forming part of Design No. 26,017, dated September 15, 1896.

Application filed July 28, 1896. Serial No. 600,853. Term of patent 7 years.

To all whom it may concern:

Be it known that I, HUBERT C. HART, a citizen of the United States, residing at Unionville, in the county of Hartford and State of Connecticut, have invented and produced a new and original Design for Knife or Fork Handles; and I do hereby declare the following to be a full, clear, and exact description of the same, reference being had to the accompanying drawings, forming a part thereof.

The present invention has for its object to provide a new and useful design for knife and fork handles, substantially as shown in the drawings and hereinafter described and claimed.

Figure 1 of the drawings represents a side elevation of a table-knife, showing the handle thereof, embodying my design and the dotted lines over the blade illustrating its application to a fork; Fig. 2, a cross-section of the handle, taken on line x x of Fig. 1.

In the accompanying drawings, A represents the handle of a knife or fork slightly

tapering and rounded at its outer end, as shown. A smooth raised surface a forms the central portion of each side of the handle, which is surrounded by two longitudinal lines of beads b . Upon the outer side of these lines of beads is a raised border c , which border extends around the handle on both sides thereof, and at the ends of the handle are ornamental scrolls d , which extend between the lines of beads and upon the raised surface of the handle, as shown in Fig. 1 of the drawings.

Having now fully described my invention, what I claim as new, and desire to secure by Letters Patent, is—

The design for a knife or fork handle substantially as herein shown and described.

In testimony whereof I affix my signature in presence of two witnesses.

HUBERT C. HART.
